UNITED STATES PATENT OFFICE.

JAMES H. BELL, OF PHILADELPHIA, PENNSYLVANIA.

TIMING DEVICE FOR PIGEONS.

1,130,247.

Specification of Letters Patent.

Patented Mar. 2, 1915.

Application filed May 10, 1913. Serial No. 766,663.

To all whom it may concern:

Be it known that I, JAMES H. BELL, of Philadelphia, in the county of Philadelphia and State of Pennsylvania, have invented 5 certain new and useful Improvements in Timing Devices for Pigeons, whereof the following is a specification, reference being had to the accompanying drawings.

The invention relates more particularly 10 to timing devices for pigeons, wherein a receiver is formed for a countermark, which receiver is locked in closed position by devices controlling the timepiece.

An object of the invention is to provide 15 a case for the timepiece, which is made in two sections adapted to be secured together, each section of the case carrying a timepiece, and the receiver and controlling devices therefor.

20 A further object of the invention is to provide a device of the above character, with a supporting member in each section of the case, on which is mounted the timepiece and controlling lever therefor, where- 25 by the assembling and adjusting of the parts may be facilitated.

These and other objects will in part be obvious and will in part be hereinafter more fully described.

30 In the drawings, Figure I, is an end view of a timing device embodying the improvements. Fig. II, is a longitudinal sectional view through the same. Fig. III, is a trans- 35 verse sectional view on the line III, III, of Fig. II. Fig. IV, is a transverse sectional view on the line IV, IV, of Fig. II.

The invention consists generally in providing a cylindrical case, which is divided centrally thereof, and the other ends of 40 which are closed. The sections of the case are pivotally joined together by one member being threaded into the other, and these communicating parts of the sections are perforated so that said perforations may 45 be brought into alinement, and a sealing wire placed therethrough, for sealing the sections so that they cannot be separated without breaking the seal and removing the wire. Each section of the case is also pro- 50 vided with a receiver for the countermark, taken from the leg of the pigeon, and each section of the case is also provided with a timepiece, together with controlling devices which serve to lock the receivers in closed 55 position, and to simultaneously release the timepiece associated with the receiver.

Referring more in detail to the drawings, the timing device consists of a case 1, which is preferably formed of steel, and this case is divided transversely, one of the sections 2, 60 being formed with an internal thread 3, and the other section 4, being formed with an external thread which is adapted to engage the thread on the section 2, so that when the parts are screwed together, a joint is 65 formed through which it is impossible to insert a tool, of any character to disturb the timepieces within the sections of the case. These sections are perforated as indicated at 5, in dotted lines in Fig. III. When 70 these perforations in the inner and outer parts of the sections of the case are brought into alinement, a wire may be inserted there- 75 through, and properly sealed so as to prevent the separation of the sections of the case, or any partial separation thereof, 80 which will permit the insertion of a tool without first having broken the seal and removed the wire. The section 2, of the case is provided with seating lugs 6, on which rest a ring 7, which is secured thereto by suitable screws 8. This ring forms a sup- 85 port for the timepiece 9, and said timepiece is secured thereto in any suitable way. The section 4, of the case, is also provided with 90 supporting lugs 10, on which rest a seating ring 11, which is secured thereto in the manner similar to that stated in connection with the ring 7. This seating ring 11, serves as a support for a timepiece 12. One of the seat- 95 ing rings is preferably provided with a lug 13, see Fig. III, which is pierced by an aperture adapted to register with the perforations in the case carrying the same, and the sealing wire not only extends through the perforations in the sections of the case, but also through this lug.

The section 2, of the case is formed with a recess 14. A receiver 15, is constructed with a pocket or compartment 16, which is 100 adapted to receive a countermark taken from the leg of the pigeon. This compartment is closed by the side wall of the recess in the end of the case when said receiver is moved into said recess. In Fig. II, of the 105 drawing the receiver is shown in its extreme outer position, and the pocket or compartment open to receive a countermark. The recess 14, is formed from the metal forming the case. A stem 17, carried by the receiver 110 15, extends through an opening in the bottom wall of the recess and a disk 18, secured

2
to the end of the stem limits the outward movement of the receiver. A spring 19, surrounding said stem rests at one end against the bottom of the recess, and at its 5 other end, extends into and rests against the receiver. This spring normally forces the receiver out of the recess and holds the disk 18, against the end wall of the section 2. It will be understood that there is a 10 similar recess and receiver at the opposite end of the case in the section 4.

The lever 20, is pivotally supported by the seating ring 7. The end 21, of said lever normally rests against the disk 18, and is 15 pressed against it by a spring 22. The other end of this lever 23, carries a finger which is adapted to engage the balance wheel of the timepiece with which it is associated, so as to prevent the running of 20 the timepiece, when said lever is in the position above noted. When the receiver is pushed into the recess and the spring 19, compressed, the end 21, of the lever 20, will be moved by its spring underneath the disk 25 18, which will prevent the spring 19, from expanding and forcing the receiver out of the recess. This movement of the lever 20, which locks the receiver, will also release the 30 balance wheel of the timepiece, and permit the timepiece to be set into action.

It will be understood that there is a controlling device for each receiver, at each end of the case, and that these controlling devices operate respectively upon the time- 35 pieces. Also located within the case, and carried by the seating ring is a yielding arm 24. This arm 24, is provided with a weight 25, and the end of the arm is bent so as to lie at a point adjacent the balance 40 wheel of the timepiece. Any shaking of the timepiece which would tend to accelerate or speed the timepiece, will cause said arm 24, to vibrate through the movement of the weight carried thereby, and said arm is so 45 disposed as to contact with the balance wheel and stop or retard the action of the timepiece. By this means, any attempt to speed the timepiece will result in the opposite effect of retarding the same.

50 As above noted, the case is formed preferably of steel, and any attempt to unduly influence either timepiece, through the action of a magnet or by an electric current, applied to the case, will be prevented.

55 From the above description, it will be noted that the timepiece, the controlling lever and the means for preventing the speed of each timepiece, are mounted on the supporting ring for the timepiece, thus 60 permitting the removal of the timepiece and the controlling parts for adjusting the same or the proper adjusting of the parts before the supporting ring is attached to its section of the case. When the supporting ring 65 for the time piece is seated in the section of

the case, the controlling lever, and the other parts which coöperate with the time piece are housed beneath the timepiece, within the case. This protects these parts from any accidental disturbance through the handling of the sections of the case when separated. The controlling lever 20, is operated by a finger piece 26, which projects outwardly through a suitable recess in the supporting ring.

70 While each section of the case has been described as containing a timepiece and a seating ring for supporting the same, it will be obvious from certain aspects of the invention that the case may be made in sections, having a threaded connection, and only one timepiece mounted therein, in which case, of course, only one receiver would be used, and the coöperating controlling devices between the receiver and the timepiece. The sections would in this instance be locked together in precisely the 80 same manner as above described.

85 It is obvious that minor changes in the details of construction may be made without departing from the spirit of the invention as set forth in the appended claims.

90 Having thus described my invention, I claim:

95 1. A timing device including in combination a case formed of two sections having a threaded engagement with each other, a timepiece supported by each section, each section of the case having a recess formed therein, and a receiver for a countermark associated with each recess, a device for locking each receiver in closed position and for simultaneously releasing the timepiece therefor.

100 105 2. A timing device including in combination a case formed in two sections having a threaded engagement with each other, the outer ends of each section being closed and formed with a recess, a receiver for each recess, a supporting ring adjacent the open end of each section, a timepiece mounted in each ring, a device located in each section 110 for locking the receiver associated therewith and for simultaneously releasing the timepiece.

115 120 125 3. A timing device including in combination a case formed in two sections having a threaded engagement with each other, the outer ends of each section being closed and formed with a recess, a receiver for each recess, a supporting ring adjacent the open end of each section, a timepiece mounted in each ring, a device located in each section for locking the receiver, associated therewith and for simultaneously releasing the timepiece, and means operable from a point adjacent the face of the timepiece, for resetting the locking device and releasing the receiver.

130 4. A timing device including in combina-

tion a case formed in two sections having a threaded engagement with each other, the outer ends of each section being closed and formed with a recess, a receiver for each recess, a supporting ring adjacent the open end of each section, a timepiece mounted in each ring, a device located in each section for locking the receiver, associated therewith and for simultaneously releasing the timepiece, said locking device for the receiver being mounted on the supporting ring for the timepiece, whereby said locking device may be removed with the timepiece upon the removal of the supporting ring.

15 5. A timing device including in combination a case formed in two sections having a threaded engagement with each other, the outer ends of each section being closed and formed with a recess, a receiver for each recess, a supporting ring adjacent the open end of each section, a timepiece mounted in each ring, a device located in each section for locking the receiver, associated therewith, and for simultaneously releasing the timepiece, said locking device for the receiver being mounted on the supporting ring for the timepiece, whereby said locking device may be removed with the timepiece upon the removal of the supporting ring,

30 and means for preventing the speeding of each timepiece, said means being mounted on the seating ring therefor.

6. A timing device including a cylindrical steel case formed in two sections, the outer ends of which are closed, each end of the case being provided with a recess, a receiver having a compartment for a countermark adapted to be housed in said recess, a spring normally moving said receiver out of the recess, a stem carried by each receiver and projecting through the end wall into the section supporting the receiver, a disk carried by each stem, a supporting ring mounted adjacent the open end of each section, a

timepiece mounted on each supporting ring, 45 a locking device mounted on each supporting ring, and adapted to seat underneath the disk carried by the receiver for holding the receiver in closed position, said locking device having means for engaging the balance wheel of the timepiece with which it is associated, whereby said timepiece may be stopped when the receiver is opened, and released when the receiver is moved to closed position.

50 7. A timing device including a cylindrical steel case formed in two sections, the outer ends of which are closed, each end of the case being provided with a recess, a receiver having a compartment for a countermark 60 adapted to be housed in said recess, a spring normally moving said receiver out of the recess, a stem carried by each receiver and projecting through the end wall into the section supporting the receiver, a disk carried 65 by each stem, a supporting ring mounted adjacent the open end of each section, a timepiece mounted on each supporting ring, a locking device mounted on each supporting ring, and adapted to seat underneath the 70 disk carried by the receiver for holding the receiver in closed position, said locking device having means for engaging the balance wheel of the timepiece with which it is associated, whereby said timepiece may be 75 stopped when the receiver is opened, and released when the receiver is moved to closed position, and a device for preventing the speeding of each time piece, said device being mounted on the supporting ring for the 80 timepiece with which it is associated.

In testimony whereof, I have hereunto signed my name at Philadelphia, Pennsylvania, this ninth day of May, 1913.
